CLAIM

The ornamental design for double heads fascia gun as shown and described.

DESCRIPTION

1.1 is a perspective view of a massage head of the double heads fascia gun showing our new design.

1.2 is a front view thereof.

1.3 is a back view thereof.

1.4 is a left view thereof.

1.5 is a right view thereof.

1.6 is a top view thereof.

1.7 is a bottom view thereof.

The broken lines, and surfaces trapped within, illustrate portions of the double heads fascia gun that form no part of the claimed design.
